ELECTROACOUSTIC TRANSDUCER

Robert B. Crandell, Henry C. Maulshagen, and Richard W. Samsel, Schenectady, N. Y., assignors to General Electric Company, a corporation of New York

Application October 1, 1945, Serial No. 619,726

8 Claims. (Cl. 340—10)

This invention relates to electroacoustic transducers and particularly to such devices which include piezoelectric crystals and are employed for the transmission or reception of underwater sound waves.

In apparatus for transmitting or receiving sound underwater it is necessary to provide transducers which can be submerged in water or other liquids for long periods of time without damage or deterioration. It is, therefore, necessary to provide some form of leakproof casing for the transducer through which casing the sound waves may be transmitted with minimum attenuation. For some transducers it is desirable to employ piezoelectric crystals such as Rochelle salt crystals which are soluble in water, and the casings for such transducers must prevent leakage in order to preserve the crystals. In some underwater sound systems high frequency or supersonic waves are employed. The crystals of receiving transducers operating at supersonic frequencies are constructed with dimensions most favorable to the reception of weak signals, and the higher the operating frequency the smaller must be the individual crystals in the receiving transducer. The size and shape of the crystal is selected so that the crystal will resonate at the selected frequency. In underwater supersonic apparatus such as that disclosed and claimed in application Serial No. 619,720, filed concurrently herewith in the name of Cramer W. La Pierre et al., and assigned to the same assignee, it is necessary to mount a large number of crystals in each transducer, and in the receiving transducer these crystals are very small. Rochelle salt crystals, for example, are difficult to handle and when used in underwater devices are preferably surrounded or immersed in a liquid, such as castor oil, in which they are not soluble. When the transducer includes a plurality of crystals employed to handle different signals, it is necessary to insulate each crystal against both electrical and mechanical interference. When such crystals are very small the mounting of the crystals and the connecting of the crystals to the electrical circuits thereof become extremely difficult. Accordingly, it is an object of this invention to provide in an electroacoustic transducer employing a plurality of piezoelectric crystals an improved arrangement for mounting the crystals.

It is another object of this invention to provide an electroacoustic transducer for underwater sound apparatus employing piezoelectric crystals and including an improved arrangement for mounting the crystals and for sealing the transducer against leakage.

The features of this invention which are believed to be novel are set forth with particularity in the appended claims. The invention itself, however, both as to its organization and method of operation, together with further objects and advantages thereof, may best be understood by reference to the following description taken in connection with the accompanying drawing in which Fig. 1 is a diagrammatic representation of an

underwater supersonic apparatus provided with a transducer embodying the invention; Fig. 2 represents a signal as it appears on the cathode ray tube of Fig. 1; Fig. 3 is an enlarged face view, partly in section, of the transducer employed in Fig. 1; Fig. 4 is a longitudinal sectional side elevation of the transducer shown in Fig. 3 taken on the line 4—4 of Fig. 5; Fig. 5 is a sectional elevation view on the line 5—5 of Fig. 4; and Fig. 6 is a diagrammatic view of two of the crystals and their electrodes as employed in the transducer of Figs. 3, 4 and 5.

Referring now to the drawing, Fig. 1 represents a supersonic wave receiving apparatus for the location of objects under water and which may form a part of a locating apparatus such as that described in the aforementioned La Pierre et al. application. This apparatus includes a signal receiving device 1 arranged to be mounted under water and to be rotated to pick up signals over a predetermined field, and a signal portraying cathode ray tube 2 on which the signals picked up by the device 1 appear. The receiving apparatus 1 includes a parabolic reflector 3 arranged to concentrate the signals in predetermined positions along a line of piezoelectric crystals mounted in the receiving transducer 4. During the operation of the apparatus the crystals in the receiver 4 are scanned in order by a scanner 5, and the signals are amplified by electronic amplifier 6 and are transmitted to the stationary equipment through suitable rotating connections (not shown). The signals 15 are then amplified by an intermediate frequency amplifier and detector 7 which impresses the signals on a grid 8 of the cathode ray tube 2. The operation of the scanner also provides a synchronizing signal which is employed to time the sawtooth wave sweep current generated by sweep circuits 9 and supplied to deflecting or sweep coils 10 mounted for rotation about the neck of the cathode ray tube 2. The receiving apparatus 1 is rotated continuously and the deflecting coils 10 are rotated in synchronism therewith. The cathode ray beam which is generated in the tube 2 by the operation of a cathode 11 in conjunction with a first anode 12 and a second anode 13 is swept along a radius of the fluorescent screen of the tube by operation of the coils 10, and as the coils rotate this radial movement of the beam is timed to occur each time the line of crystals in the transducer 4 is scanned. The active or energized period of the transducer is limited to a predetermined arc or portion of the circular field covered by the rotation of the receiving equipment 1. As shown in Fig. 2 a portion of a sector of the fluorescent screen of the tube 2, represented by a dotted line 14, gives a visual presentation of the field under examination and which is actively scanned during each revolution of the receiver. The transducer 4 is arranged so that when an object is present in the water in front of the receiver parabola 3 it will result in the reception of signals indicating the position and relative size of the object as shown at 15. The purpose of the plurality of crystals employed in the transducer 4 is to provide a plurality 20 of points along each of the radii scanned by the apparatus as it receives signals from the area 14. Each scanning of the transducer 4 produces signals along a single radius of the segment 14, and because of the rotation of the receiver the series of consecutive scannings 25 represent a series of radii in the segmental field under examination. If an object is present in the water in the field under examination it is represented by brighter signals as indicated at 15, the signals appearing from the scanning of a plurality of adjacent radii combining 30 to produce an image or shadowgraph of the object on the fluorescent screen.

In order that the intensity of signals received along the line scanned by the apparatus may be as great as possible, it is desirable that the crystals along the line be located at the focus points for the energy received from their respective different portions of the field. Objects directly in front of the reflector produce signals at the normal focus point for the parabola for beams parallel to the axis. The focus points for objects in the field either above or below the reflector lie along a curve which must be determined for the particular reflector under consideration and for sound at the frequency transmitted by the apparatus. The curve for the locus points for sound energy does not coincide with the curve for light, because the far greater wavelength of the sound energy must be taken into consideration. Furthermore the direction in which the flat faces of the crystals are pointed must also be taken into consideration, it being desirable to have the crystal point toward the center of that portion of the reflector from which energy is to be received as determined by the direction from which it strikes the reflector. In the construction of a practical sound receiving equipment it normally will be found necessary to design the curvature of the line of crystals in accordance with good practice to provide a compromise between several factors involved. The degree of accuracy in the location of the crystals will, of course, vary with the degree of precision required in the operation of the equipment, greater accuracy being required for greater definition of the signal portrayed on the viewing screen. In some cases, for practical reasons it may be desirable to provide two or more lines of crystals in a single surface as in the construction illustrated; obviously the curve of the line of crystals employed in this case is a compromise since the two lines of crystals are operated at different frequencies although they lie along the same locus curve.

In order to secure reliable operation of the transducer 4, it is constructed so that highly sensitive crystals having dimensions of the order necessary for resonance at the desired supersonic frequencies may be securely mounted with a minimum possibility of injury during operation. Referring now to Figs. 3, 4 and 5, the transducer 4 comprises a metal casing or body 16, and a block 17 of resilient insulating material is mounted in the casing 16 against a partition member or inwardly extending flange 18. The block 17 may be constructed of any resilient material having the desired electrical and vibration insulating properties; for example, the material sold under the trade name "Corprene" has been found satisfactory for this purpose. The flange 18 divides the casing into two compartments or chambers in open communication with one another, the upper chamber containing the block 17 and the lower chamber indicated at 19 containing the outgoing connections to the several crystals. The outer face of the block 17 indicated at 20, is constructed to include two inwardly sloping faces approximating a curve which would represent the locus of focus points of the parabolic mirror 3 for the sound energy at the desired frequency. In the face 20 of the block 17 there are molded or otherwise suitably formed a plurality of recesses 21 arranged in a row along one side of the face of the block and a plurality of smaller recesses 22 arranged in a second row along the other side of the face. Slits 23 and 24 are formed along the outer sides of the rows of recesses, and conductor ribbons or electrodes 25 and 26, respectively, are pressed into the slits so that the conductors 25 and 26 enter each recess of the rows of recesses 21 and 22 respectively. On the opposite sides of the recesses there are inserted individual electrodes 27 and 28 respectively, and between the electrodes are the piezoelectric crystals constituting the signal sensitive elements of the transducer. The larger crystals indicated at 29 are mounted in the recesses 21 and the smaller crystals 30 in the recesses 22. The faces of the

crystals are flush with the face of the block 17. The dimensions of the crystals and the electrodes are such that the crystals are held in position in the recesses and between the electrodes by friction maintained because of the resilience of the material of the block 17. This arrangement for mounting crystals to be frictionally retained in a resilient block is described and claimed in a copending application of Richard W. Samsel, Serial No. 619,724, now abandoned, filed concurrently herewith and assigned to the same assignee. In order to insure sufficient and uniform pressure throughout the rows of crystals, the block 17 is constructed with an upper reduced portion in which the crystals are mounted, and metal clamping bars 31 are provided which may be drawn together against this portion of the block by screws 32. Each of the electrodes 25, 26, 27 and 28 is provided with conductors 33, 34, 35 and 36, respectively, whereby the electrodes may be connected in the electrical circuits of the apparatus. These conductors extend from the electrodes through the resilient block 17 to the side opposite the face 20. The electrodes 25 and 26 which are common to all the crystals in their respective rows are grounded, the conductors 33 and 34 being connected to a common ground conductor 37 as indicated in Fig. 6. It is essential that each conductor be positioned so that it may be identified and properly connected in the circuit, and for this purpose spacing bars 38 and 39, and a clamping bar 40 are provided in the chamber 19 below the opening formed by the flange 18. As indicated in Fig. 5 the leads to the several conductors may be clamped between the bars 38, 39 and 40 and may then be connected to their respective ones of the conductors 33, 34, 35 and 36. The conductor leads are preferably insulated cables having metallic sheaths, all the sheaths being grounded when clamped between the bars 38, 39 and 40; this provides effective shielding for the several signal conductors and minimizes cross talk. The chamber 19 is sealed by a plate 41 provided with a sealing gasket 42 and access to the chamber for adjustment of the spacing blocks and connections may be had by removing this plate. The connections to the several conductors are taken out through a conduit connection 43 communicating with the chamber 19 at one side thereof; air or other gas under pressure may be admitted through the connection 43 to minimize the likelihood of leakage into the casing. In some types of apparatus it has been found desirable to employ Rochelle salt crystals; these crystals are soluble in water, and a protective casing is necessary to prevent water from coming in contact with the crystals. Furthermore, when any crystals in a group operate on different signals, water would short circuit the signal energy and cause cross talk between the several crystals; an insulating liquid is therefore required in such multiple signal transducers, whether or not the crystals are soluble in water. In order to prevent loss of signal strength the surrounding casing must be such that there is little attenuation of the signal due to the passing of the sound through the casing wall to the crystals. Rochelle salt crystals may be protected satisfactorily by immersion in suitable liquids, for example, castor oil; and, in the transducer illustrated, the crystals are maintained immersed in a body of castor oil 44 which is contained within a casing formed by a rectangular cup or cover member 45. The cover is constructed of a flexible waterproof material, such as a suitable type of rubber, having sound transmission characteristics as nearly as possible the same as those of the water in which the apparatus is to be used. The cover 45 has a flange portion 46 and this portion, together with a metal collar 47, fits about the block 17 and is clamped to the edge of the casing 16 by a plurality of screws 48, a gasket 49 being located between the collar 47 and the case. The collar 47 also extends over the edge portion of the block 17 between

the block and the clamps 31, and when the screws 48 are tightened the casing is not only sealed against leakage between the flange 46 of the cover and the case but, in addition, the collar 47 presses the block 17 against the flange 18 and effectively prevents leakage of the castor oil 44 between the block and the casing. In the event that there is a tendency toward leakage of castor oil through the block 17 along the conductors, the lower side of the block within the flange 18 may be coated with a suitable leak-preventing cement; the face of the block and crystals may also be coated with a material to prevent leakage of the oil into the recess. Since the clamps 31 are metallic, they may tend to produce reflected signals with resulting distortion to the desired signals, and for minimizing such reflections an insulating collar or gasket 50 may be cemented or otherwise secured to the upper sides of the clamps 31.

The entire assembly as described is simple and compact and retains the crystals in their required positions for the reception of relatively weak signals with minimum distortion and interference or cross talk between individual circuits. The construction also facilitates the mounting of the crystals in the desired line representing the line of focus points for a reflector used therewith. Furthermore, although the crystals may be extremely small, for example, the longest dimension of the crystals 22 when desired for a frequency of 750 kilocycles may be less than a tenth of an inch, still the resiliency of the block 17 maintains the crystals in position and in good electrical contact with their respective electrodes throughout the operation of a system such as that shown in Fig. 1.

While the invention has been illustrated in connection with an electroacoustic transducer for receiving supersonic sound vibrations under water, other applications will readily be apparent to those skilled in the art; for example, the mounting of crystals in a resilient block in the manner disclosed may obviously be employed for the mounting of crystals in transmitting transducers. It is not, therefore, desired that the invention be limited to the particular construction illustrated and described, and it is intended by the appended claims to cover all modifications that fall within the spirit and scope of the invention.

What we claim as new and desire to secure by Letters Patent of the United States is:

1. In an underwater sound receiving system of the type employing a curved surface reflector, an electroacoustic transducer for receiving signals from such reflector and comprising a support, a block of resilient insulating material mounted on said support and having a row of recesses along one face thereof, piezoelectric crystals embedded in said recesses to form a line of crystals, said face of said block being shaped to conform to a curve approximating the line of focus points for signals reflected onto said transducer and said crystals having faces lying substantially along said line, and electrode means engaging said crystals for conducting individual signals from said crystals.

2. An electroacoustic transducer comprising a support, a block of resilient insulating material mounted on said support and having a row of recesses therein, said block also having a slit providing communication between said recesses, piezoelectric crystals embedded in said recesses to form a line of crystals, a common strip electrode for said crystals arranged in said slit in contact with said crystals, individual electrodes in said recesses on the side opposite said slit each contacting a respective one of said crystals, and means for compressing said block to maintain said crystals and said electrodes in contact.

3. An electroacoustic transducer comprising a case having a partition wall forming two chambers in open communication, a block of resilient insulating material in one of said chambers and closing the opening between

said chambers, said block having a recess therein on the outwardly facing side thereof, a piezoelectric crystal in said recess, contact electrodes in said recess in engagement with said crystal, conductors for said electrodes extending through said block and through the opening between said chambers into the other of said chambers, a resilient closure member for said one chamber, a body of oil filling the space in said one chamber between said closure member and said block, and clamping means for pressing said closure member and said block into sealing engagement with said case to prevent the leakage of oil from said one chamber.

4. An electroacoustic transducer comprising an open case, a block of resilient insulating material in said case, a piezoelectric crystal mounted in said block, a wall member constituting a stop for determining the position of said block in said case, a resilient gasket mounted on the outer face of the wall of said case about the opening therein, a collar resting against said gasket and against an adjacent face area of said block, a cover for said case constructed of resilient insulating material and having an edge portion resting against said collar, a second collar arranged over said edge portion, a body of insulating liquid filling said case, and means for clamping said second collar and said case together for compressing said gasket and the edge portion of said cover to prevent leakage of said insulating liquid and for pressing said first collar against said block to urge said block against said wall member.

5. An electroacoustic transducer comprising a support, an elongated block of resilient insulating material mounted on said support, said block having a row of recesses therein opening on one face thereof, a plurality of piezoelectric crystals each arranged in a respective one of said recesses, contact electrodes for said crystals in said recesses laterally of said row, and clamping means arranged longitudinally of said block for compressing said block to retain said crystals in said recesses and in contact with said electrodes throughout the length of said row.

6. An electroacoustic transducer comprising a casing having two open sides and an inwardly extending flange near one of said open sides, a block of resilient insulating material resting against said flange and closing said one side of said casing, a plurality of piezoelectric crystals embedded in an outer face of said block, individual conductors for connecting said crystals in an electrical circuit, said conductors extending through said block into said casing, a spacing rack for said conductors within said casing, a conduit connection for leading said conductors from said casing, and a removable cover for the other of said sides for sealing said casing and for affording access to said rack.

7. An electroacoustic transducer comprising a casing having two open sides and an inwardly extending flange near one of said open sides, a block of resilient insulating material resting against said flange and closing said one side of said casing, a plurality of piezoelectric crystals embedded in an outer face of said block, individual leads for connecting said crystals in an electrical circuit, said leads extending through said block into said casing, a plurality of concentric cables having the center conductors thereof connected to said leads, a conducting spacing rack for said concentric cables arranged within said casing for connecting said casing and the outer conductors of said cables, a conduit connection for leading said cables from said casing, and a removable cover for the other of said sides of said casing for sealing said casing and for affording access to said rack.

8. An underwater sound receiving system of the type employing a curved surface reflector, an electroacoustic transducer for receiving signals from such reflector and comprising a support, a block of resilient insulating material mounted on said support and having a row of recesses along one face thereof, piezoelectric crystals embedded in said recesses and having exposed faces lying approxi-

mately along the line of focus points for signals reflected onto said transducer, and electrode means engaging said crystals for conducting individual signals from said crystals.
